Primary Examiner — Mimoso De(74) *Attorney, Agent, or Firm* — Kolisch Hartwell, P.C.(57) **CLAIM**

We claim the ornamental design for a chair with footrest, as shown and described.

DESCRIPTION

FIG. 1 is an upper-right perspective view of a chair with footrest according to an embodiment of the invention.

FIG. 2 is a lower-left perspective view of FIG. 1.

FIG. 3 is a top plan view of FIG. 1.

FIG. 4 is a bottom plan view of FIG. 1.

FIG. 5 is a left side elevation view of FIG. 1.

FIG. 6 is a right side elevation view of FIG. 1.

FIG. 7 is a front elevation view of FIG. 1; and,

FIG. 8 is a rear elevation view of FIG. 1.

The unclaimed environment is represented by thick, evenly spaced, dash-dot-dot-dash lines, and forms no part of the claimed design.
